UNITED STATES PATENT OFFICE.

SEWARD N. MIGHELL, OF CHICAGO, ILLINOIS.

COAL-MINING MACHINE.

1,346,966.

Specification of Letters Patent. Patented July 20, 1920.

Application filed July 10, 1916. Serial No. 108,351.

To all whom it may concern:

Be it known that I, SEWARD N. MIGHELL, a citizen of the United States, residing in Chicago, in the county of Cook and State of Illinois, have invented certain new and useful Improvements in Coal-Mining Machines, of which the following is a specification.

This invention relates to that class of mining machines which are adapted to be used 10 for mining coal or other material.

The principal object of the invention is to provide a simple, economical and efficient mining machine adapted to be used for cutting or mining coal or similar material, and 15 adapted to be moved with facility to different positions with respect to the material to be operated upon.

Other and further objects of the invention will appear from the following description, 20 and from an inspection of the accompanying drawings which are made a part hereof.

In the accompanying drawings:—

Figure 1 is a plan view of a mining machine constructed in accordance with my invention and improvements, with a portion of the cutter bar or cutting chain supporting arm broken away, and with the cutting chain omitted;

Fig. 2, a detail plan view of the outer portion of the cutter bar or cutting chain supporting arm, with a portion of the cutting chain in operative position thereon;

Fig. 3, a view in central transverse vertical section, taken on line 3 of Fig. 1 looking 35 in the direction of the arrow;

Fig. 4, a view in vertical section taken on line 4 of Fig. 1 looking in the direction of the arrow, and showing the main frame and mechanism on the main frame in elevation, 40 with the cutting chain mechanism omitted and the outer portion of the cutter bar broken away;

Fig. 5, a view in front elevation of the machine shown in Figs. 1, 3 and 4, showing 45 the means for supporting the main frame and one extremity of the main feed screw or worm—the means for supporting the opposite extremity of the main feed screw being of identical construction and therefore omitted from said view;

Fig. 6, an enlarged detail view taken on line 6 of Fig. 1, looking in the direction of the arrow, and showing the pawl and ratchet mechanism for operating the rotative screw

or worm for moving the cutter bar upon its 55 pivot or vertical axis;

Fig. 7, an enlarged detail view in transverse horizontal section taken on line 7 of Fig. 4, looking in the direction of the arrow, and showing the rotative crank disk or 60 head and adjustable wrist pin for operating the pawl and ratchet mechanism shown in Fig. 6, to move the cutter arm upon its pivot or axis;

Fig. 8, a view in end elevation of the end 65 portion of the bottom frame or track as it would appear when seen from line 8 of Fig. 5, looking in the direction of the arrow;

Fig. 9, an enlarged detail view in vertical longitudinal section, taken on line 9 of Fig. 70 1, looking in the direction of the arrow, and showing the main hollow feed screw and its support, and the means for operatively connecting said feed screw with the main frame; one of the safety plates being shown 75 in a broken condition, in broken lines;

Fig. 10, an enlarged view in longitudinal vertical section, taken on line 10 of Fig. 2, looking in the direction of the arrow, and showing the construction of the outer end 80 portion of the cutter arm;

Fig. 11, an enlarged transverse detail view in vertical section taken on line 11 of Fig. 2, looking in the direction of the arrow, and showing the cutter arm with the cutting 85 chain mechanism in operative position thereon;

Fig. 12, a detail view in elevation of a portion of a cutting chain, with the cutting bits removed; and

Fig. 13, an enlarged detail view in transverse vertical section through the cutter arm, taken on line 13 of Fig. 1, looking in the direction of the arrow.

In constructing a mining machine in accordance with my invention and improvements I provide a bottom frame or track 1 having horizontal lateral bottom frame portions 2, 2, and an upright track portion 3, extending beneath an upper movable main 100 frame 4, to be supported thereby. The bottom frame or track is formed by preference of a pair of angle irons laid side by side and connected so that the horizontal flange portions 2 extend laterally in opposite directions from the central connected vertical track portions 3, the main frame 4 being supported upon and movable longitudinally 105

with respect to the track or bottom frame thus provided. A hollow non-rotative main feed-screw or worm 5, is mounted in parallel relation to the longitudinal track portion 3 and supported by the bottom frame of which the track portion 3 forms a part. The main feed-screw 5 is, by preference, connected with and secured in operative position upon the bottom frame 1 in such a manner that when the feed-screw is subjected to excessive stresses and strains when the machine is in operation, the feed-screw will be released or permitted to rotate so as to prevent injury to the parts, but will be held non-rotatably when the machine is in operation under normal conditions or when such excessive stresses and strains as would endanger or permit injury to the mechanism are absent.

A very satisfactory and efficient means for securing the main feed-screw in position is shown in the drawings in which upright end frame members 6, each by preference of substantially identical construction, are firmly and rigidly secured to opposite ends of the bottom frame or track 1, said end frame members each being provided with an opening 7 in which is mounted a flanged collar 8, into which the corresponding end of the main feed screw extends. Each collar 8 has an outer flange portion 9 adapted to engage the outside of the corresponding end frame member 6, and a sleeve or bushing 10 is interposed between the ring or collar 8 and the end of the main feed-screw which is encircled by such bushing. A cap or washer 11 is mounted on the outside of each of the collars 8 respectively and endwise beyond the adjacent end of the main feed-screw. Each of the caps 11 has an opening therethrough, and a connecting rod 12 extends longitudinally through the hollow main feed-screw and through the openings in the caps or washers 11 at the opposite ends of the rod and feed-screws, and threaded nuts 13 are mounted in threaded engagement with the opposite ends of the rod 12, and each in engagement with the outer surface of the corresponding cap or washer 11. An inner collar or securing ring 14 encircles and is secured in fixed relation to the main feed-screw 5 by means of a key 15 and set screw 16, or other suitable securing means, and a washer or annular friction member 17 is interposed between the collar 14 and the adjacent frame member 6, as indicated in Fig. 9. I prefer to mount a collar 14 and a ring or washer 17 upon and in fixed relation to each of the ends of the feed-screw 5, respectively, rather than at one end only. The connection between the main feed-screw and its supports may thus be tightened or loosened at either end of the feed-screw as desired by merely tightening or loosening the corresponding nut 13. The end washers 11 or caps 11 are, by preference, made of cast

metal of sufficient strength to enable the feed-screws to be held non-rotatably during the operation of the machine under normal conditions, but sufficiently weak or brittle to enable the washer or washers 11 to be broken so as to release and permit the rotation of the main feed-screw whenever it is subjected to excessive stresses and strains. It is obvious that the collars 14 are adapted to be drawn tightly into engagement with the washer 17 and the end frame member 6 by rotating the corresponding nut 13 in one direction, and may be loosened partially or to any desired extent by rotating such nut in an opposite direction, thus enabling the collar or collars 14 to rotate with the screw 5 whenever the latter is subjected to excessive stresses and strains. Each collar 14 is provided with peripheral notches 18 adapted to be engaged by a spanner wrench, so as to permit the rotation of the screw 5 by rotating such collar or collars when desired, to relieve any binding of the parts which may occur, or for any other reason. It is obvious that the collars 14 may be thus rotated, when desired, upon loosening the corresponding nuts 13 so as to release the pressure of the nuts upon the adjacent safety plates 11.

It is also plain that excessive strains upon the normally fixed feed screw 5—such as are liable to occur when the cutter strikes an unusual obstruction—will tend to rotate said normally stationary feed screw as well as the collars 14 and 8 and safety plates 11 at the opposite ends of the feed screw, and that, when such strains are sufficiently great to cause the actual rotation or endwise movement of the feed screw, and the rotation of the collars 14 and 8, one or both of the safety plates 11 will thus be twisted or bent and distorted and broken, thus releasing the collars 14 and 8 and the feed screw, and permitting the latter to rotate with its engaged nut members 76 and 82, without injury to the machine, until the operation of the machine can be stopped. (See Fig. 9.) The strains would be transmitted from the nut members or nuts 76 and 82 to the feed screw and the collars 14 and 8 and the plate 11 or plates 11.

The upper or main frame 4 may be of any desired construction suitable for supporting the mechanism to be mounted thereon, and for enabling such frame and the mechanism supported thereby to be moved longitudinally of the track 3 or bottom frame 1, when the latter is stationary, and for permitting the track or bottom frame 1 to be moved with facility to any desired position with respect to the main frame 4. The main frame 4, when constructed as shown in the drawings, comprises a bottom frame portion 19, upright and frame members 20 and 21, having horizontal outwardly

projecting flanges 22, 22, a front frame member or plate 23, a rear frame member or upright frame member 24 and a top plate or frame member 25. (See Figs. 1, 3 and 5.)

A suitable source of power, such for instance as an electric motor 26, which may be of any desired, ordinary and well known or suitable form, is mounted upon the main frame 4, to which such motor is secured in a suitable manner, for instance, by means of bolts 27, which extend through suitable openings 28 in the flanges 22 of the upright end frame members 20 and 21 respectively, and into the adjacent bottom portion 29 of the casing or frame of the motor. (See Figs. 1 and 5.)

The top plate 25 is also provided with openings 30 adapted to receive securing bolts 20 to be anchored in the frame portion 29 of the motor for securing the latter in position on the main frame. Anti-friction flanged guiding-rollers 31 are rotatively mounted in the main frame 4 with their vertical axles 25 32 journaled in suitable bearings in the front depending frame portion 33. (See Figs. 3 and 5.) These flanged anti-friction rollers engage the side edge of a horizontal guiding or track member 34, which is secured to and projects outward forward or laterally with respect to the upright track portion 3, already described. (See Figs. 3 and 5.) Upper anti-friction rollers 35 are mounted upon horizontal studs or pins 36, 35 and lower anti-friction rollers 37 are mounted upon similar horizontal supporting studs 38, the upper rollers 35 being in engagement with the top face, and the lower rollers 37 being in engagement with the bottom face of the horizontal guiding track member 34, already described, and said studs 36 and 38 being anchored in the depending frame portion 33, already described. (See Figs. 4 and 5.)

45 A main driving shaft 39 is rotatively mounted in suitable bearings 40, 41, in the main frame and, by preference, in parallel relation to the power shaft 42 of the motor. This main driving shaft 39 is operatively connected with the source of power by means of which it is to be driven, as follows: A gear 43 is mounted upon and adapted to rotate with the main-driving shaft 39 to which said gear wheel is secured by means of a key 44; and a spur gear wheel 45 is mounted upon and adapted to rotate with the motor or power shaft 42 to which said gear 45 is secured by means of a spline 46, in such a manner as to permit the gear 45 to be moved longitudinally of the motor shaft into and out of toothed engagement with the gear wheel 43. An inner spur gear wheel 47 is fixed to the main drive shaft 39, and a spur gear wheel 48 is mounted in position to encircle the power

shaft 42 and is connected with and in fixed relation to the spur gear wheel 45 by means of a sleeve 49, said gear wheels 48 and 45 being spaced apart a sufficient distance to permit an intermediate speed changing and reversing pinion or gear wheel 50 which is rotatively mounted on a stub shaft 51 and in toothed engagement with the gear wheel 47, to extend between and out of engagement with said gears 48 and 45 when the latter is in engagement with gear wheel 43, and to permit gear wheels 48 and 50 to be engaged when the gear wheel 45 is moved out of engagement with the gear wheel 43. The direction of rotation of the main drive shaft 39 with respect to the power shaft 42 may thus be changed by shifting the connected gears 48 and 45 in the required direction longitudinally of the power shaft. (See Fig. 3.) The main driving shaft 39 is also provided with a sprocket wheel 52 adapted to be operatively connected with a truck or vehicle (not shown) for conveying the machine as a whole from place to place when desired. A worm 53 is fixed to the rotative main driving shaft 39, and an intermediate or countershaft 54 is mounted in suitable bearings in the main frame and at right angles with respect to the main driving shaft, and provided with a worm-wheel 55 fixed to said counter-shaft and in toothed engagement with the worm 53. A plurality of spur gear wheels 56 and 57 are mounted upon and adapted to be operatively connected with and disconnected from the counter-shaft, each of said gear wheels being provided with a clutch member 58 fixed thereto. A pair of clutch members 59 are mounted upon and movable longitudinally of the counter-shaft 54 into and out of engagement with the clutch members 58 respectively, said clutch members 59 being operatively connected with the counter-shaft by means of splines 60 in such a manner as to cause the clutch members 59 to rotate with, but to be movable longitudinally of the counter-shaft, as suggested.

50 Suitable means is provided for operating the clutch members 59, and comprises in its construction a reciprocating clutch operating member 61, having yoked portions 62 in engagement with peripherally slotted portions 63 of the clutch members 59, respectively, said reciprocating member 61 being provided with end-wise projecting arm portions 64 and 65, slidably mounted in bearings 66 and 67, respectively, and extending in parallel relation to the shaft 54, already described. These projecting arm portions 64 and 65 are thus adapted to support and permit the reciprocation of the clutch operating member 61, and the clutch operating lever 68 is operatively connected with one of said arm members by means of a pivot pin 69, 130

and is pivotally mounted upon the main frame of the machine by means of a supporting pivot 70. (See Figs. 1 and 5.) Mounted upon and in toothed engagement with the 5 non-rotative feed-screw 5 is a pair of spur gear wheels 71 and 72, which are, by preference, connected in fixed relation to each other by means of a sleeve 73, one end of which is rigidly connected with the gear 71 10 by means of screws 74, and the other end of which is connected with the gear wheel 72 by means of screws 75, or other suitable securing means. The gear wheel member 71 is in toothed engagement with the 15 gear wheel member 56, already described, and has an inner threaded portion 76 encircling and in threaded engagement with the non-rotative main feed-screw 5. An end-wise projecting sleeve or hub portion 77, 20 of the gear wheel member 71, is rotatively supported in the end frame member 20, already described, and is provided with a metallic bushing 78 adapted to form a suitable support for the sleeve or journal portion 77, 25 which is encircled by such bushing, and a thrust bearing, preferably in the form of a pair of metallic rings, 79 and 80, having a series of hardened steel balls 81 mounted in annular grooves in said rings, is interposed 30 between the frame member 20 and the adjacent portion of the gear wheel 71. The gear wheel 72, already described, is provided with an endwise projecting inwardly threaded nut portion 82 in threaded engagement with 35 the main feed screw 5, and rotatively mounted in a suitable metallic bushing 83 in the end frame member 21, and a thrust bearing 84, by preference, of substantially the same construction as the thrust bearing last 40 above described, is interposed between the end frame member 21 and the adjacent end portion of the gear wheel member 72. An intermediate idler gear wheel member 85 is 45 rotatively mounted on a suitable support such as a non-rotative stub shaft 86 and in toothed engagement with the gear wheel member 72 and with the gear wheel members 57, respectively. The stub shaft 86 is supported by the end frame member 21. (See 50 Fig. 1). The gear wheel member 71, with its inner threaded portion, and the gear wheel member 72, with its inner threaded portion, each form a gear wheel and an inwardly threaded nut in threaded engagement with the non-rotative main feed-screw 5, adapted to cause the main frame 4, already described, to be moved in one direction longitudinally of the main feed-screw and the track, when said combined gear wheel 55 and nut members are rotated in one direction, and to cause said main frame 4 to be moved in the opposite direction longitudinally with respect to said main feed-screw and track when the connected gear wheel 60 and nut members 71 and 72 are rotated in 65

an opposite direction, provided the bottom frame or track 1 is secured in fixed position. It is obvious that the combined gear and nut members 71 and 72 are adapted to be rotated in one direction when the gear wheel 56 is 70 connected in fixed relation to the counter-shaft 54 by means of the clutch member 59, and in an opposite direction when the gear wheel 57 is connected in fixed relation to said counter-shaft by means of the clutch 75 member 59', and that said clutch members 59, 59' are operatively connected with and adapted to be operated by the hand lever 68, as already suggested. It should also be noted that the projecting end portions 64 80 and 65 of the reciprocating clutch operating mechanism are each adapted to engage a stop 87 at the adjacent end of the bottom frame or track 1, when the main frame has been moved to the extreme limit of its path 85 of movement in either direction longitudinally of the main screw-feed 5 and bottom frame or track 1, there being a stop 87 at each end of the bottom frame 1, respectively. (See Fig. 5.) It is obvious that when either 90 of the endwise projecting portions 64 and 65, respectively, comes in contact with the stop 87, the clutch mechanism, including clutch members 59 and 59' will be operated, and released and the movement of the main 95 frame 4 stopped automatically.

A cutter bar or cutting chain supporting arm 88 is pivotally mounted upon the main frame 4 and comprises in its construction a main body portion 89, having vertical side 100 flange portions 90 to which longitudinally slotted lateral chain supporting and guiding members 91 are secured by means of bolts 92 and nuts 93, or similar securing means, the inner extremity of the central main body 105 portion 89 being adjustably connected with and supported by an inner hub portion 94, which is pivotally mounted upon and encircles an upright hollow pivot or vertical axle 95, which is fixed to the bottom of the 110 main frame portion 19, and projects upward therefrom. (See Figs. 1, 2, 3, 10, 11 and 13.) An annular collar 96 is rigidly secured in fixed relation to the hollow pivot or axle 95, and projects outward horizontally beyond 115 the periphery of said axle and in supporting engagement with the hub portion 94 of the cutter bar. The hub portion 94 is provided with a projecting arm or shank 97, which is by preference forked at its outer extremity, as indicated in Figs. 3 and 13, and the main body portion 89 of the cutter bar is provided with elongated slots 98 through which extend headed bolts or pins 99, which are anchored in the arm portions of the 120 shank 97 and secured in position by means of nuts 100, as shown in Figs. 1 and 13. A horizontal adjusting screw 101 is fixed to the central portion of the shank 97 in position to extend longitudinally with respect 125 130

to the central portion of the main cutter bar 88, and through an upright transverse stud 102 on the main body portion 89 of the cutter bar; and adjusting nuts 103 and 104 are 5 mounted upon and in threaded engagement with the non-rotative screw 101, and on opposite sides of the stud 102. (See Figs. 1, 3 and 13.) The main central body portion 89 of the cutter bar is also provided with 10 elongated slots 105, through which extend vertical headed bolts 106, which are anchored in the outer extremity 107 of the shank 97, and secured to said shank by means of nuts 108. (See Figs. 1 and 3.) The outer 15 extremity of the main body portion 89 is provided with a slotted top plate 109 and a slotted bottom plate 110 secured thereto by means of bolts or screws 111, and adapted to provide a bayonet slot 112 between said top 20 and bottom plates, which slot is curved and communicates with, and forms a continuation of, and a curved connection between bayonet slots 113 in the channel members 91, already described. A cutting chain 114, 25 comprising a multiplicity of pivotally connecting links 115 and 116, having side guiding flange portions 117, adapted to be securely held in sliding engagement with the bayonet slot portions 112 and 113, is slidably 30 mounted in said slotted portions of the cutter bar and in operative engagement with the sprocket teeth 118 of a sprocket wheel 119 which is fixed to the lower extremity of a vertical rotative chain-operating shaft 120 35 by means of a key 121, or other suitable securing means. (See Figs. 2, 3 and 11.) The main body portion 89 of the cutter bar is thus adapted to be adjusted to different positions longitudinally with respect to the 40 shank 97 by turning the adjusting nuts 103 and 104 in the required direction for tightening or loosening the cutter chain. The vertical shaft 120 to which the sprocket 119 is secured extends upward from said sprocket 45 through the axial center of the hollow axle or pivot 95, and is provided at its upper end with a beveled pinion or gear wheel 122 fixed to the upper extremity of said shaft by means of a key 123, and in toothed engagement 50 with a beveled pinion 124 which is mounted upon and adapted to be connected with, and disconnected from operative engagement with the main driving shaft 39. The beveled pinion 124 has a clutch member 125 upon and 55 in fixed relation thereto, and a movable clutch member 126 is mounted upon and so connected with the main driving shaft 39 by means of a spline 127 as to cause said clutch member to constantly rotate with said 60 main driving shaft when the latter is in operation, and to permit said clutch member 126 to be moved into and out of clutching engagement with the beveled pinion 124 and the clutch member 125 on said pinion. A 65 plate 128 is mounted in position to form a suitable support or bearing for the beveled gear wheel 122, and a hollow metallic bushing 129 is interposed between the inner wall of the hollow axle 95 and the shaft 120, and encircles and forms a suitable bearing for 70 said shaft. A worm wheel 130 is secured in fixed relation to the hub member 94 by means of a key 131 or similar securing means, and a shaft 132 is relatively mounted in suitable bearings in the main frame adjacent to 75 and in parallel relation to the counter-shaft 54, and provided with a worm 133 in toothed engagement with said worm wheel 130 on the hub member 94 of the cutter bar. The worm 80 133 is secured in fixed relation to the rotative worm supporting shaft 132 by means of a key 134, or similar securing means. (See Fig. 3.) From the foregoing description it will be readily understood that when the main driving shaft 39 is operatively connected with the vertical chain-driving shaft 120 by operatively connecting the gear 124 with the main driving shaft by means of the clutch members 125 and 126, the rotation 85 of the main driving shaft will operate the cutting chain which is provided with a series of cutting bits 135 removably mounted in the sockets 136 and secured in position by means of set screws 137 so as to project outward at the desired angle for cutting coal 90 or other material to be operated upon. It is also apparent that such operation of the chain will be accomplished, no matter in what position the cutter bar may be with respect to the main frame of the machine, or 95 at what angle the cutter bar may extend with respect to the main feed-screw 5 and bottom frame or track 1. It is also obvious that the cutter bar is adapted to be partially rotated upon its axis or vertical pivot either 100 while the cutting chain is thus being driven, or while the main driving shaft 39 is disconnected from the beveled gear wheel 124, and thus not operatively connected with the chain driving shaft 120. It is also obvious 105 that the chain may thus be driven by the rotation of the main driving shaft either while the cutter bar is in fixed relation to the pivot or vertical axle 95, or while said cutter bar is being swung about its pivot, as desired. 110 With the clutch members 59 and 59' in the positions shown in Fig. 1, and the gear members 57, 85 and 72 operatively connected with the main drive shaft by means of the clutch member 59' it is obvious that 115 the movement of the main frame toward the right in said figure will cause the projecting end 65 of the clutch-operating member 61 to come into contact with the stop 87 at the right side of said figure, thereby causing the clutch member 59' to be disconnected or thrown out of clutching position. The clutch member 59 is thus in position to 120 be readily thrown into clutching engagement with the clutch member 58 so as to 125 130

operate gears 56 and 71, thereby reversing the direction of rotation of the gear 71 and the connected nuts or nut members comprising gears 71 and 72 and threaded nut members 76 and 82, thereby reversing the direction of movement of the main frame. The continuation of the movement toward the right of Fig. 1 will, of course, cause the projecting end portion 64 of the clutch-operating member 61 to engage the corresponding stop 87 at the left extremity of the track, and thus again automatically stop the movement of the main frame which carries the pivoted cutter bar and cutting chain mechanism.

In order to provide suitable and efficient means for moving the cutter bar upon its pivot or axis to different adjusted positions at different angles with respect to the main frame of the machine and with respect to the main feed-screw and bottom frame or track member 1, and for rotating the cutter bar upon its pivot preparatory to or during the operation of cutting coal, or other material to be operated upon, and in order to enable the speed of rotation, or rotary movement, of the cutter bar to be regulated and increased or diminished with respect to the speed of movement of the cutting chain, the chain operating mechanism and the movement of the main frame as it is caused to travel longitudinally of the main feed-screw and bottom frame or track, and in order to provide means for changing the direction of movement of the cutter bar upon its pivot with facility and in a simple and efficient manner, the worm supporting shaft 132 above described, is provided with a toothed ratchet wheel 138 fixed thereto, said ratchet wheel having teeth 139 adapted to enable the shaft and the worm 133 thereon to be rotated in opposite directions alternately as desired. A reciprocating or oscillating lever 140 is pivotally mounted upon the shaft 132 adjacent to the ratchet wheel 138, and provided with a spring-pressed pawl or sliding bolt 141 mounted upon said lever and adapted to operatively engage the teeth 139 of the ratchet wheel 138. The pawl or sliding bolt 141 is slidably mounted in a socket or aperture 142 in the reciprocating lever member 140, and is provided with a compression spring 143 mounted in the socket and in engagement with an enlarged shoulder portion 144 of the pawl member, and adapted to yieldingly hold the ratchet engaging end 145 of the pawl in engagement with the teeth of said ratchet wheel. The ratchet engaging end of the pawl 141 has an oblique end surface portion 146 on one side, adapted to permit the pawl member to pass from one to the other of the ratchet teeth successively in one direction of movement of the pawl, and the opposite side of the pawl from said inclined surface portion

is of such form as to extend into operative engagement with a substantially radial surface portion of an adjacent ratchet tooth, and of any of the ratchet teeth successively as they come into position to be engaged by the pawl, so as to cause the rotation of the ratchet wheel in the desired direction, as the operating lever 140 is reciprocated. The pawl 141 is provided with a laterally projecting pin 147 adapted to extend into a transverse slot 148 in the socket portion 149 of the lever member 140, and a thumb nut or handle 150 is mounted upon the outer end of the pawl member 141 and adapted to enable the latter to be turned one half of a complete revolution from the position in which it is shown in Fig. 6, or to inverted position, so as to cause the ratchet wheel 138 and the worm supporting shaft 132 to be rotated in an opposite direction, when desired, and without changing the character of the movement of the operating lever 140, or the mode of operation of the crank and link mechanism by means of which such lever is reciprocated. In order to reverse the position of the pawl member 141, as indicated, it is only necessary to move it outward against the tension of the spring until the pin 147 is outside of the slot 148 and then turn the pawl or sliding bolt to the desired position corresponding with the desired direction of rotation of the ratchet wheel. By simply turning the pawl one-fourth of a complete revolution from that in which it is shown in Fig. 6, and permitting the pin 147 to enter the relatively shallow slot 151 the pawl will be kept out of engagement with the ratchet wheel, and the lever 140 and pawl may be reciprocated without rotating the shaft 132 or causing the rotation or movement of the cutter bar upon its axis.

A crank disk 152 is fixed to the end of the shaft 54 already described, and is provided with a transverse bayonet slot 153, having flanged wall portions 154 between which extends a crank pin 155 having an enlarged or headed portion 156 located on the inside of the slot and adapted to be securely held in any desired adjusted position in the slot. (See Figs. 1, 4 and 7.) The connecting link 156, which is curved so as to prevent it from coming into contact with the screw 5 or any part of the machine which would interfere with its operation, is connected at one end with the crank pin or wrist pin 155 by means of a nut 157 on said wrist pin, and at its opposite end with the lever 140 by means of a pivot pin 158.

I provide one or any suitable number of jacks 159 adapted to hold the track member firmly in stationary position during the normal operation of the machine. These jacks are also adapted to be used for securing the main frame and cutter bar in stationary position while the track member is being

5 moved with respect to the main frame from one position to another preparatory to being again secured in stationary position suitable for enabling the mining or cutting operations of the machine to be begun or continued.

10 The jack 159 shown in the drawings comprises in its construction a screw or helically threaded main body portion 160 which is seated, by preference removably and loosely, in a socket member 170 provided with a lower shank portion adapted to be pivotally connected with a link or clevis member 170' having forked arm portions 15 171 adapted to be removably secured to a suitable frame portion of the machine, such, for instance, as a channel member 173 located at either end of the track member, by means of a pivot pin 174. A pivot pin 172 20 which extends at right angles to the pivot pin 174 forms a pivotal connection between the socket member 170 and the link member 170'. The screw is thus adapted to be swung to any desired angular position with respect 25 to the machine, as required. A hand wheel 175 having a screw-threaded axial perforation therein is mounted upon and in threaded engagement with the screw; and the screw extends into the open bottom end of a pipe or 30 tube 176 which may be of any desired suitable length for engaging a ceiling, wall, or other abutment. A suitable brace is thus provided adapted to be mounted in engagement with any desired suitable part of the machine, 35 for holding the same in stationary position. The bottom end of the pipe 176 is adapted to engage the outer end face of the hub of the wheel 175. The jack is thus adapted to be removably secured in position to engage 40 either a lug 177 at either end of the track or a boss 178 on the frame.

45 A mining machine constructed as above described is adapted to be used in cutting entries, as well as in the making of an initial or sumping cut, and in making the main cut in the operation of mining coal or other material, or in undercutting.

50 In operation, in making a main cut, for instance, the main track or bottom frame 1 is firmly secured in stationary position by means of jacks, such as the jack 159 above described. In case the cutting is to be begun in a corner of a room and to be continued along the face or from one extremity to the 55 other of a face of greater length than can be cut without changing the position of the main track member to complete the cut, the main track member is secured in stationary position in approximately parallel relation 60 to the face of the coal or material to be cut or operated upon. In making the initial cut the cutter bar may be moved to operative position at any desired angle with respect to the track. In case it is desired to have 65 the cutter bar swing upon its pivot during

the operation of the cutting chain mechanism the clutch member 126 is moved into engagement with the clutch member 125 on the gear wheel 124, thereby causing the main driving shaft 39 to be operatively connected with the cutting chain mechanism, so as to operate the latter; and the pawl 141 on the pawl-operating lever 140 is adjusted to the position shown in Fig. 6, so that the reciprocation of the pawl-operating lever 140 will cause the worm shaft 132 to rotate in the direction necessary to move the cutter bar on its pivot in the direction necessary to hold the cutting chain mechanism in cutting position and feed the cutter bar and chain mechanism toward the material to be operated upon. In case the cutter bar is to be swung and the cutting mechanism operated as suggested without moving the main frame longitudinally of the track, it is only necessary to leave the clutch members 59 and 59' in their intermediate or clutch releasing position. In case the main frame is to be moved along longitudinally of the track, the clutch member 59, or else the clutch member 59' is moved into clutching position, according to the direction the main frame is to be moved. The main frame is thus adapted to be automatically moved along longitudinally with respect to the track while the cutter arm is in any desired position into which it is adapted to be adjusted, or at any desired angle with respect to the track, and while the cutter mechanism is in operation. When the main frame has thus been fed longitudinally of the track from one end to the other of the track and it is found desirable to move the track to another position with respect to the main frame and with respect to the face of the coal or material to be operated upon, the cutter bar may be secured in stationary position together with the main frame, by means of jacks adapted to engage the main frame and the ceiling or wall or other abutment, and the clutch member 126 and pawl 141 are moved to releasing or inoperative position. The main driving shaft is then set in operation by being operatively connected with the motor or source of power, and the required one of the clutch members 59, 59' moved into clutching engagement with the adjacent gear wheel 56 or 57 as the case may be, according to the direction in which the track is to be moved. The operation of the main driving shaft will thus cause the track to be moved endwise beneath the main frame while the latter is stationary, and when the track has thus been moved to the desired position, the main frame is permitted to again move along the track during the operation of the cutting mechanism, the jacks being removed from engagement with the main frame so as to permit such movement of the

main frame, and being secured in position to hold the track in stationary position during the continued operation of the machine. When the opposite side or extremity of the 5 face of the coal or material is approached or reached and it is desired to stop the movement of the main frame upon the track and to continue the operation of the cutting chain mechanism with the cutter bar in 10 motion upon its axis the clutch members 59 and 59' are both moved to their intermediate or clutch-releasing position, and the clutch member 126 on the main driving shaft, and the pawl member 141 on the re- 15 ciprocating lever 140 are retained in or moved into operative position, so as to cause the cutting chain mechanism to be operated simultaneously with or during the swinging of the cutter arm upon its vertical pivot. 20

It is obvious that the main frame is adapted to be fed longitudinally of the track while the cutter bar is in parallel relation to the track or in position to extend 25 endwise beyond the adjacent end of the track at either extremity thereof, or while the cutter bar is in position to extend at any desired angle with respect to the track and with respect to the path of movement 30 of the main frame, as already suggested.

I claim:—

1. In a mining machine, the combination of a portable track, a main frame supported upon and movable longitudinally of the 35 track, a cutter bar mounted on the main frame, a cutting chain supported by the cutter bar, a non-rotative main feed screw mounted in fixed relation to the track, threaded nut mechanism rotatively mounted 40 on the main frame and in threaded engagement with said main feed screw, a main drive shaft rotatively mounted in the main frame and adapted to be operatively connected with a source of power and with said 45 cutting chain, for driving the latter, means for operatively connecting said main drive shaft with said threaded nut mechanism, for moving the main frame with respect to the main feed screw and track, reversible gear 50 mechanism upon the main frame and connected with the main drive shaft and adapted to operatively connect said shaft with the source of power for reversing the direction of rotation of the main drive shaft, and means for changing the direction of rotation of said threaded nut mechanism with 55 respect to the direction of rotation of the main drive shaft.

2. In a mining machine, the combination 60 of a portable track, a main frame supported upon and movable longitudinally of the track, a cutter bar pivotally mounted on the main frame, a cutting chain supported by the cutter bar, means for operating the cutter bar upon its axis, a non-rotative main

feed screw mounted in fixed relation to the track, threaded nut mechanism mounted on the main frame and in threaded engagement with said main feed screw, a main drive shaft rotatively mounted in the main frame 70 and operatively connected with a source of power and with said cutting chain mechanism for driving the same, means for operatively connecting said main drive shaft with said threaded nut mechanism, for moving 75 the main frame with respect to the main feed screw and track, cutter bar operating means comprising pawl and ratchet mechanism operatively connected with said last-mentioned connecting means and with the 80 cutter bar, for operating the same, and means for changing the direction of rotation of said threaded nut mechanism with respect to the direction of rotation of the main drive shaft. 85

3. In a mining machine, the combination of a portable track, a main frame supported in movable relation to the track, a cutter bar mounted on the main frame, a cutting chain supported by the cutter bar, a non-rotative 90 main feed screw mounted in fixed relation to the track, threaded nut mechanism rotatively mounted on the main frame and in threaded engagement with said main feed screw, a main drive shaft rotatively mounted 95 in the main frame and operatively connected with a source of power and with said cutting chain, for driving the same, means for operatively connecting said main drive shaft with said threaded nut mechanism, cutter bar operating means comprising pawl and ratchet mechanism operatively connected with said last-mentioned connecting means and with the cutter bar, for operating 100 the same, means for reversing the direction of rotation of the main drive shaft, and means for changing the direction of rotation of said threaded nut mechanism upon the main feed screw. 105

4. In a mining machine, the combination 110 of a portable track, a main frame supported in movable relation to the track, a cutter bar mounted on the main frame, a cutting chain supported by the cutter bar, a non-rotative main feed screw mounted in fixed relation 115 to the track, threaded nut mechanism rotatively mounted on the main frame and in threaded engagement with said main feed screw, a main drive shaft rotatively mounted in the main frame and operatively connected with a source of power and with said cutting chain, for driving the same, means for operatively connecting said main drive shaft with said threaded nut mechanism, cutter bar operating means comprising pawl 120 and ratchet mechanism operatively connected with said last-mentioned connecting means and with the cutter bar, for operating the same, means for disconnecting the main drive shaft from the cutting chain, and 125 130

means for changing the direction of rotation of said threaded nut mechanism upon the main feed screw.

5. In a mining machine, the combination of a track member, a main frame mounted in movable relation to the track member, a cutter bar supported by the main frame, cutting chain mechanism upon the cutter bar, a main driving shaft rotatively mounted in the main frame and operatively connected with a source of power, a threaded main feed screw fixed to the track member, threaded nut mechanism mounted on the main frame and in threaded engagement with said main feed screw, means for operatively connecting the threaded nut mechanism with the main driving shaft, for enabling the main frame and the track member to be moved relatively to each other, cutter bar operating means comprising pawl and ratchet mechanism operatively connected with said last-mentioned connecting means and with the cutter bar, for operating the same, means for operatively connecting the cutting chain mechanism with the main driving shaft, and means for reversing the direction of rotation of the nut mechanism, to change the direction of movement of the main frame and track relatively to each other.
- 10 6. In a mining machine, the combination of a track member, a main frame supported upon and movable longitudinally of the track, cutting mechanism supported and movable with the main frame, means for operating the cutting mechanism, a main feed screw, securing means acting to secure said feed screw in normal non-rotative engagement with the track member, said securing means being adapted to automatically release and permit the rotation of said feed screw when the latter is subjected to excessive strains, a nut member rotatively mounted on the main frame and in toothed engagement with said normally non-rotative main feed screw, and means for rotating said nut member.
- 15 7. In a mining machine, the combination of a track member, a main frame supported upon and movable longitudinally of the track, cutting mechanism supported and movable with the main frame, means for operating the cutting mechanism, a main feed screw, securing means acting to secure said feed screw in normal non-rotative engagement with the track member, said securing means being adapted to automatically release and permit the rotation of said feed screw when the latter is subjected to excessive strains, a nut member rotatively mounted on the main frame and in toothed engagement with said normally non-rotative main feed screw, and means for rotating said nut member.
- 20 8. In a mining machine, the combination of a track member, a main frame supported upon and movable longitudinally of the track, cutting mechanism supported and movable with the main frame, means for operating the cutting mechanism, a main feed screw, securing means acting to secure said feed screw in normal non-rotative engagement with the track member, said securing means being adapted to automatically release and permit the rotation of said feed screw when the latter is subjected to excessive strains, a nut member rotatively mounted on the main frame and in toothed engagement with said normally non-rotative main feed screw, and means for rotating said nut member.
- 25 9. In a mining machine, the combination of a track member, a main frame supported upon and movable longitudinally of the track, cutting mechanism supported and movable with the main frame, a main driving shaft rotatively mounted in the main

frame and operatively connected with the cutting mechanism, a main feed screw, means for yieldably securing the main feed screw in normally non-rotative engagement with the track member, and adapted to release and permit the rotation of the main feed screw when the latter is subjected to excessive stresses and strains, a nut member rotatively mounted on the main frame and in toothed engagement with said normally non-rotative main feed screw, and means for operatively connecting the main driving shaft with said nut member.

10 10. In a mining machine, the combination of a track member, a main frame supported upon and movable longitudinally of the track, cutting mechanism supported and movable with the main frame, means for operating the cutting mechanism, a main feed screw, securing means acting to secure said feed screw in normal non-rotative engagement with the track member, said securing means being adapted to automatically release and permit the rotation of said feed screw when the latter is subjected to excessive strains, a nut member rotatively mounted on the main frame and in toothed engagement with said normally non-rotative main feed screw, and means for rotating said nut member.

Signed at Chicago, Illinois, July 6, 1916.
